United States Patent

Des. 235,926

Patented July 15, 1975

235,926

SYRINGE PUMP UNIT

Raymond G. Olson, Niles, Ill., assignor to Baxter
Laboratories, Inc., Morton Grove, Ill.

Filed Aug. 15, 1973, Ser. No. 388,535

Term of patent 14 years

Int. Cl. D15—02; D24—02

U.S. Cl. D83—1 F

FIG. 4

FIG. 5

FIG. 6

FIG. 7

FIG. 1 is a front perspective view of a syringe pump unit showing my new design;

FIG. 2 is a front elevational thereof;

FIG. 3 is a top plan view thereof;

FIG. 4 is a left elevation thereof;

FIG. 5 is a rear elevation thereof;

FIG. 6 is a right side elevational thereof; and

FIG. 7 is a bottom plan view thereof.

The broken lines are shown for illustrative purposes only.

I claim:

The ornamental design for a syringe pump unit, as shown and described.
